UNITED STATES PATENT OFFICE.

HARRY VISSERING, OF CHICAGO, ILLINOIS, ASSIGNOR TO HARRY VISSERING & COMPANY, OF CHICAGO, ILLINOIS, A CORPORATION OF ILLINOIS.

TRACK-SANDING APPARATUS.

1,109,092.

Specification of Letters Patent.

Patented Sept. 1, 1914.

Application filed April 17, 1912. Serial No. 691,458.

To all whom it may concern:

Be it known that I, HARRY VISSERING, a citizen of the United States, and a resident of Chicago, in the State of Illinois, have invented certain new and useful Improvements in Track-Sanding Apparatus, of which the following is a specification.

My present invention relates to sand ejecting apparatus and more particularly to the track sanding apparatus commonly used at this day for applying sand adjacent the points of contact of the locomotive wheels with the rails and has special reference to the provision of a structure adapted for such application of sand upon the operation of the valve employed by the engineer in the operation of the air brakes.

The principal objects of my present invention are the provision of a form of sanding apparatus so arranged that upon movement of the air brake controlling valve and more particularly movement thereof to "emergency" position, sand will be automatically ejected from the apparatus; the provision of means whereby the engineer may simultaneously operate the brakes and the sanding apparatus; the provision of combined means whereby the air brake and sanding apparatus may be operated either simultaneously or independently; the provision of an improved form of controlling valve for the purpose referred to; the provision of an improved form of material restraining means or sand trap having the required connections for such purpose and generally to improve sand strewing systems, together with such further objects as may hereinafter appear.

Track sanding apparatus as arranged for use at this day, as known to me, lacks provision of effective means for simultaneously actuating the air brake and the track sanding apparatus, since the manipulation of the separate controlling valves is required. Of late no little trouble has been experienced in handling heavy trains, more particularly heavy fast passenger trains equipped with modern high-speed air brake equipment, in the way of skid flat wheels arising from "emergency" or other extra hard application of the air brakes without simultaneous actuation of the track sanding apparatus, and this especially during damp weather when the rail has a tendency to become

greasy. I have therefore devised the present system, wherein the air for operating the sander may be taken from a special connection on the engineer's brake valve, so that upon actuation of the brakes the sanding apparatus will be automatically actuated so as to efficiently apply the sand to the rail before the pressure of the brake on the wheels becomes sufficient to lock the wheels, cause them to skid, and consequently present flat spots. In order to avoid waste of sand and ensuing fruitless expense not only for sand and air pressure wasted but also for care and maintenance of the equipment, and to prevent the engineer from cutting out the emergency sanding apparatus and thereby rendering it inoperative at the time when it is most required, I preferably dispose the connection between the engineer's brake valve and the sand trap at a point where sand will be admitted from the valve to the trap only when the valve is moved to emergency position, thus preventing frittering away of sand when the valve is on the lap or running position or moved only to position for ordinary service application of the brakes, and to this end care is desirably used to avoid the implacement of any stop-cock or cutout-cock of any kind between the brake valve and the trap.

In gaining the stated objects and overcoming the disadvantages referred to I have provided the constructions illustrated in the accompanying drawings wherein—

Figure 1 is a diagrammatic elevational view of a railway locomotive having my improved track sanding apparatus applied thereto; Fig. 2 is an enlarged fragmentary plan view of part of the locomotive of Fig. 1; Figs. 3 and 4 are respectively an elevational view and a plan view of a form of duplex sand trap employed in the construction illustrated in Fig. 1; Figs. 5, 6 and 7 are respectively a plan, an elevational and an end view of a modified form of sand trap; and Fig. 8 is a plan view, partly in horizontal section, of a form of engineer's brake valve employed by me in connection with the device of Fig. 1.

Referring first more particularly to Fig. 1, it will be noted that I have here illustrated somewhat conventionally a locomotive having wheels 11 adapted to ride on rails 12. As a receptacle for containing a supply of

sand the locomotive 10 is provided with a sand dome 13 with which communicate on both sides of the locomotive one or more traps, as indicated at 14, 14', 15, 15', which 5 serve to restrain the flow of sand from the receptacle 13 save when the apparatus is actuated. The traps referred to communicate with delivery pipes 16, 17, having nozzles 18, 19, adapted to deliver sand adjacent 10 the points of contact of the wheels 11, 11 with the rails 12, the pipe 16 being disposed for delivery of sand in front of the wheels and the pipe 17 being disposed for delivery of sand to the rear thereof as is desired 15 when the engine is running backward. For ejecting sand contained in the traps 14, 15 through the pipes 16, 17 in alternation, I provide in manually operated actuating means, the fluid conductor pipes indicated 20 at 20, 21, connected to the traps 14, 15 and to a three-way controlling valve 22 connected as by a pipe 23 to a source of fluid pressure, such as the main air reservoir 24 of the air brake system, which is supplied by 25 an air compressor (not shown).

On referring to Fig. 2, it will be observed that the traps 14, 14' are homologous and that the traps 15, 15' are likewise homologous; furthermore that by the employment 30 of a suitable connection such as the pipes 20', 21' the manually operated sander just described is preferably so arranged that air is admitted simultaneously into the traps 14, 14' or 15, 15'. Again reverting to Fig. 1 35 it will likewise be apparent that I have here illustrated somewhat diagrammatically an air brake system including the main air reservoir 24 above referred to, an engineer's brake valve 25 connected to such reservoir 24 40 by a pipe 26, a brake cylinder 27 connected to the brake valve 25 by a pipe 28, a brake lever 29 fulcrumed at 30 and operable by fluid pressure admitted to said cylinder 27 through the pipe 28, the lever 29 being connected by a brake rod 31 to a brake beam 45 fulcrumed at 32 to the framing 33 which beam carries the brake head 34 provided with a shoe 35 bearing on one of the wheels 11 in the customary manner. For admitting air to the traps 14, 14 and 14', 14', and thereby ejecting sand from such traps and applying it to the point of contact between the wheels 11 and the rail 12, simultaneously 50 with the operation of the air brakes, and especially upon emergency application thereof, and independently of any operation of the valve 22, I provide on the brake valve 25 a special port 36 (see Fig. 8) connected by a pipe 37 and a branch thereof 37' to portions 55 of the traps 14, 14' shortly to be described, such port 36 being preferably so arranged as to be placed in communication with the reservoir 24 only when the handle of the 60 brake valve 25 is moved to the emergency 65 position indicated in Fig. 8.

Inasmuch as the traps 14, 14' are homologous I will now proceed to the description of the trap 14 only, in connection with Figs. 3 and 4, from which it may be seen that the trap body 40 is adapted to be attached at 70 some convenient place adjacent the dome 13 by means of bolts passing through the holes 41, 42 and 43, is provided with suitable connections at 44, 44' to receive the pipes 37 and 20, has an opening at 45 communicating 75 with the dome 13, and has at 46 a connection adapted to receive the discharge pipe 16. Arranged transversely through the body 10 between the connection 45 and the closing plug 47 is a passage 48 communicating by passages 49, 49', 50, 50' with a transversely arranged passage 51 leading to the connection 46, the passages between the connections 44 and 44' and the passage 48 having interposed therein nozzles 52 and 53, 80 and the passages 49-50, 49'-50' having openings to the atmosphere (normally closed by caps 54, 54') whereby they may be cleaned. The construction just described in the present embodiment of my invention 85 cares for the sanding of the wheels when moving forwardly whether the sand be discharged manually through the operation of the sander valve 22 or automatically through the operation of the brake valve 25. For 90 sanding the wheels when the engine is moving rearwardly a similar arrangement of trap may be employed, but ordinarily I find it sufficient to form preferably integrally with the trap 14 just described, a similarly 95 constructed trap 15 wherein I employ a connection 44^a, a nozzle 52^a, an opening 45^a, 100 passages 49^a, 50^a and a connection 46^a. Referring now more particularly to the device of Figs. 5, 6 and 7, it will be observed, 105 that the device here illustrated is in all substantial respects similar to that of the device of Figs. 3 and 4 save that in lieu of the duplication of the portions 49 and 50, as indicated at 49' and 50', I introduce air 110 from the pipe 37 into the trap 14^b through the connection 44^b and air from the pipe 20 through the connection 44^c, each of said connections communicating with the passage 45^b and respectively having interposed in 115 such passage nozzles as indicated at 52^b and 53^b. Inasmuch as in ordinary service application of the brakes, it is desirable to conserve the air supply as far as may be, whereas in emergency application of the 120 brakes the sanding apparatus is actuated by air vented in such application and no such need of conservation of pressure exists, and in the latter case it is desirable to supply a larger quantity of sand to the rails, I preferably give the nozzle 52 a larger orifice and hence greater carrying capacity than the nozzle 53, and likewise make the orifice of the nozzle 52^b larger than that of the nozzle 53^b, thereby permitting the passage 125 130

of a heavy blast of air through the pipe 37 when the valve 25 is moved to emergency position.

From the foregoing description of my invention it will be observed that in the operation thereof, either the front or rear sander may be operated manually by manipulation of the duplex cab valve 22, and that upon manipulation of the brake valve 25, in the present embodiment of my invention, on an emergency application of the brakes, the front sander will be operated automatically and simultaneously with the operation of the brakes without concurrent manipulation of the valve 22, thus insuring at all times adequate and efficient supply of sand adjacent the point of contact of the wheels with the rails, at the time such sand is most needed.

Having thus described my invention and illustrated its use, what I claim as new and desire to secure by Letters Patent is:

1. A trap comprising a body having connection to a receptacle for material; a plurality of air inlet connections, one whereof is arranged for downward discharge into the trap, and a continuous connection to a common delivery pipe, communicating therewith and arranged for the discharge of material therethrough upon admission of air through either of the inlets.

2. A trap comprising a body having connections to a receptacle for material and to a discharge pipe, a connection to a sander controlling valve, and a connection to an engineer's brake valve.

3. A trap comprising a body having connections to a receptacle for material and to a discharge pipe, a connection to a sander controlling valve, and a connection to an emergency port on an engineer's brake valve.

4. A trap comprising a body having connection to a receptacle for material, a plurality of air inlet connections, and a connection to a discharge pipe, one of said air inlet connections being arranged below the other thereof and arranged for discharge into the trap.

5. A trap comprising a body having connection to a receptacle for material, a plurality of air inlet connections, and a continuous connection to a common delivery pipe, one of said air inlet connections being arranged at an angle to another thereof and adapted for downward discharge into the trap.

6. A trap comprising a body having connection to a receptacle for material, a plurality of air inlet connections, and a connection to a discharge pipe, one of said air inlet connections being arranged below the other thereof and at an angle thereto and adapted for downward discharge into the trap.

7. A trap comprising a body having con-

nection to a receptacle for material, a plurality of air inlet connections, and a connection to a discharge pipe, one of said air inlet connections being arranged at an angle to another thereof and having larger capacity than such other and both being adapted for discharge into the trap.

8. In an apparatus of the character described, in combination, with a sand dome, a trap communicating therewith, an ejector connected to said trap, an engineer's brake valve having a discharge port, an air reservoir, a brake cylinder, and connections between said brake valve and said brake cylinder and said air reservoir, and between said discharge port and said sand trap.

9. In an apparatus of the character described, in combination, with a sand dome, a trap connected thereto, an air reservoir, a brake cylinder, a brake valve having a discharge port, and a sander controlling valve, said controlling valve having connections to said air reservoir and said sand trap, and said brake valve having connections to said air reservoir and said brake cylinder, and having independent connections to said trap.

10. In an apparatus of the character described, in combination, with a sand dome, a duplex trap having forward and rearward ejector portions, an air reservoir, a brake cylinder, a brake valve having a discharge port, and a sander controlling valve, said controlling valve having a connection to said air reservoir and having independent connections to the front and rear portions of said trap, and said brake valve having connection to said brake cylinder and said air reservoir and an independent connection to the forward ejector portion of said trap.

11. In an apparatus of the character described in combination with a sand dome, an air reservoir, a brake cylinder, a brake valve having a discharge port, and a sander controlling valve, of a trap comprising a body portion having connections to said sand dome, and to a discharge pipe, and a plurality of air inlet connections, said controlling valve having connections to said air reservoir and one of the inlet connections of said sand trap, and said brake valve having connections to said air reservoir and said brake cylinder, and an independent connection to the other of said air inlet connections.

12. In an apparatus of the character described, in combination with a sand dome, an air reservoir, a brake cylinder, a brake valve having a discharge port, and a sander controlling valve, of a duplex trap having forward and rearward ejector portions communicating with said sand dome, one of said portions having a plurality of air inlet connections, said controlling valve having a connection to said air reservoir and having independent connections to the front and

rear portions of said trap, and said brake valve having connections to said brake cylinder, and said air reservoir and independent connection to one of the said air inlets 5 of the said trap.

13. A track sanding apparatus comprising, in combination with an engineer's brake valve having a connection to a source of fluid pressure, a receptacle for material 10 provided with means for retarding the flow of material therefrom, and manually operated means for ejecting material from said sand receptacle, a connection between said brake valve and said sand receptacle where- 15 by said sanding apparatus may be automatically actuated upon manipulation of said brake valve, or manually actuated by said manually operated means.

14. A track sanding apparatus comprising, in combination with an engineer's brake valve having a connection to a source of fluid pressure and to a brake cylinder, a receptacle for material provided with means for retarding the flow of material therefrom, 20 and manually operated means for ejecting material from said sand receptacle, a connection between said brake valve and said sand receptacle whereby said sanding apparatus may be automatically actuated upon 25 manipulation of said brake valve and admission of pressure to the brake cylinder, or manually actuated by said manually operated means.

15. A trap comprising a body having a 30 connection to a receptacle for material, a plurality of air inlet connections, two of which are adapted to discharge into the body of the trap, and one of which has a larger orifice than the other thereof, and a 35 connection to a common discharge pipe.

16. A trap comprising a body having a connection to a receptacle for material, a plurality of air inlet connections, two of which are adapted to discharge into the 40 body of the trap, and one of which is of a larger capacity than the other thereof, and a connection to a common discharge pipe.

17. A trap comprising a body having a connection to a receptacle for material, a 45 plurality of air inlet connections, two of which are adapted to discharge into the body of the trap and each being provided with a blast nozzle and one nozzle being larger than the other thereof, and a connection to a common discharge pipe.

18. A trap comprising a body having connections to a receptacle for material and to a discharge pipe, and connections to a sander controlling valve and to an engi-

neer's brake valve, said last mentioned connections being each provided with a nozzle and the nozzle in the connection to the brake valve being larger than the nozzle in the connection to the controlling valve.

19. A trap comprising a body having connections to a receptacle for material and to a discharge pipe, and connections to a sander controlling valve and to an engineer's brake valve, the connection to the brake valve being larger than the connection to the controlling valve.

20. A trap comprising a body having connection to a receptacle for material, a plurality of air inlet connections, two of which are adapted to discharge into the body of the trap, and a connection to a discharge pipe, one of said air inlet connections being arranged below the other thereof and having a larger capacity than such other.

21. A trap comprising a body having connection to a receptacle for material, a plurality of air inlet connections, and a connection to a discharge pipe, one of said air inlet connections being arranged below and at an angle to another thereof and having a larger capacity than such other.

22. A trap comprising a body having connection to a receptacle for material, a plurality of air inlet connections, and a connection to a discharge pipe, one of said air inlet connections being arranged at an angle to another thereof and having larger capacity than such other and being adapted for downward discharge into the trap.

23. A trap comprising a body having a sand restraining abutment, a connection to a receptacle for material, a plurality of air inlet connections, one whereof is arranged for downward discharge into the trap, and a connection to a common delivery pipe, communicating therewith and arranged for the discharge of material therethrough upon admission of air through either of the inlets.

24. A trap comprising a body having a sand restraining abutment, a connection to a receptacle for material, a plurality of air inlet connections, and a connection to a common delivery pipe, one of said air inlet connections being arranged at an angle to another thereof and adapted for downward discharge into the trap.

In testimony whereof I have hereunto signed my name in the presence of the two subscribed witnesses.

HARRY VISSERING.
